(57) **CLAIM**

The ornamental design for a toy building frame, as shown and described.

DESCRIPTION

FIG. 1 is a top perspective view of a toy building frame in accordance with a first embodiment of our new design; FIG. 2 is a top plan view thereof;

FIG. 3 is a left side elevation view, the right side elevation view being identical thereto;

FIG. 4 is a rear elevation view thereof;

FIG. 5 is a bottom plan view thereof;

FIG. 6 is a front elevation view thereof;

FIG. 7 is a top perspective view of a toy building frame in accordance with a second embodiment of our new design;

FIG. 8 is a top plan view thereof;

FIG. 9 is a left side elevation view thereof, the right side elevation view being identical thereto;

FIG. 10 is a rear elevation view thereof;

FIG. 11 is a bottom plan view thereof;

FIG. 12 is a front elevation view thereof;

FIG. 13 is a sectional view taken along line 13-13 in FIG. 8;

FIG. 14 is a partial perspective sectional view taken along line 14-14 in FIG. 8;

FIG. 15 is a top perspective view of a toy building frame in accordance with a third embodiment of our new design;

FIG. 16 is a top plan view thereof;

FIG. 17 is a left side elevation view thereof, the right side elevation view being identical thereto;

FIG. 18 is a rear elevation view thereof;

FIG. 19 is a bottom plan view thereof;

FIG. 20 is a front elevation view thereof; and,

FIG. 21 is a sectional view taken along line 21-21 in FIG. 16. The broken lines illustrate portions of the toy building frame that form no part of the claimed design.

The oblique shade lines in FIGS. 15-21 represent a transparent or translucent surface and not surface ornamentation.

1 Claim, 10 Drawing Sheets
